DRAFT RIGGING

Byers W. Kadel, Baltimore, Md., assignor to The Symington Company, New York, N. Y., a corporation of Maryland

Application February 3, 1931, Serial No. 513,219

16 Claims. (Cl. 213—7)

This invention relates to draft rigging, and, more particularly, to an arrangement involving a plurality of gears acting in series when compressed in one direction, and in tandem when compressed in the other direction.

The principal object of my invention, generally considered, is the provision of two draft gears at each end of a railway vehicle, so arranged that they act in series for absorbing buffering forces, and in tandem for cushioning draft forces.

Another object of my invention is to arrange cushioning mechanism with railway draft rigging so that an equivalent cushioning or energy-absorbing capacity is provided for both buffering and draft forces, but the associated drawbar is allowed to move a greater distance in one direction than in the other.

A still further object of my invention is to provide cushioning mechanism on a railway vehicle which is adapted to absorb an equal amount of energy whether it is subjected to draft or buffering forces, but which offers a greater resistance to one kind of force than to the other.

A still further object of my invention is the combination of a pair of cushioning devices with rigging on a railway vehicle so that said devices act in tandem when the rigging is subjected to draft forces, and thereby offer a maximum resistance to such forces, with the allowance of a minimum of slack, while operating in series under the action of buffering forces, so that a maximum amount of movement to full compression is provided, thereby protecting the vehicle and lading by reducing the buffering forces which are necessary to compress said devices.

Other objects and advantages of the invention relating to the particular arrangement and construction of the various parts will become apparent as the description proceeds.

Referring to the drawings illustrating my invention, the scope whereof is defined by the appended claims:—

Figure 1 is a vertical longitudinal section taken between the draft sills of a railway vehicle and showing one embodiment of my draft rigging with associated cushioning devices in side elevation, a portion of the associated yoke and the connecting draft keys being shown in section.

Figure 2 is a plan of the arrangement shown in Figure 1, portions being shown in horizontal section.

Figure 3 is a view similar to Figure 2, but showing a modification.

Figures 4 and 5 are transverse sectional views taken, respectively, on the correspondingly num-

bered lines of Figure 3, looking in the direction of the arrows.

Figures 6 and 7 are views corresponding, respectively, to Figures 1 and 2, but showing a further modification.

Figures 8, 9, 10 and 11 are diagrams representing the cushioning effect of the front and rear gears, singly, in series, and in tandem.

Referring to the drawings in detail, like parts being designated by like reference characters, 10 and first considering the embodiment of my invention illustrated in Figures 1 and 2, I have shown a pair of friction draft gears 1 mounted between sills 2, and each having an associated front follower 3 supported between the sills by 15 keys 4 passing through slots 5 in the followers and slots 6 in the front cheek plates 7 and slots 8 in the rear cheek plates 9 and sills 2.

Each draft gear 1 may be of any suitable construction, but, in the embodiment disclosed, comprises a housing 10 provided with interlocked blocks 11 formed with inclined friction surfaces 12 engaged by corresponding surfaces 13 on associated wedge blocks 14, resilient means, in the form of plate springs 15, being provided for urging said wedges 14 apart and into engagement with the wedge blocks 11, said wedges being provided with inner outwardly extending flanges or lugs 16 interlocking over the inner ends of the wedge blocks 11 for holding the parts in assembled relation. The releasing means illustrated for the gear involve an intermediate follower 17 and two sets of release springs 18 preferably separated by a spacing plate 19.

Embracing the friction draft gears and associated followers is a vertical yoke 20 connected to an associated drawbar 21 by means of a horizontal key 22, the ends of which are received in the front slots 23 in the foremost cheek plates 7 and sills of the car. Although the drawbar 21 is, in the present embodiment, shown as the stem or shank of a swivel butt coupler, it will be understood that I do not wish to be limited to this showing.

The slots 24 in the yoke receiving the key 22 are elongated rearwardly of the normal position of the rear edge of said key so that, although the key serves for the transmission of draft forces from the drawbar to the yoke, it permits rearward movement of the key and coupler for the compression of the front cushioning device or gear 1 from the drawbar to the yoke, it permits rearward movement of the key and coupler for the compression of the front cushioning device or gear 1 independently of yoke movement. The slots 23 are elongated forwardly and rearwardly of the key 22 so that movement of said key in both directions is permitted. The lugs or backstop 25,

which serves as rearward limiting means for the gears or cushioning devices 1, has sufficient clearance with respect to the rearward portion 26 of the yoke so that rearward movement of said yoke 5 for the compression of the rear cushioning device or gear 1 by the transverse web or bridge wall 27 of said yoke is permitted. It will be clear that said transverse bridge wall of the yoke serves as a spacer between the forward and rearward 10 cushioning devices, or between the front draft gear 1 and the front follower for the rear draft gear 1, as well as a follower member between said parts, or it may also be considered as the rear end of forward yoke-acting means especially 15 for the front draft gear 1.

In order to cause the gears to operate in tandem under the action of draft forces, the keys 4 serve as individual front stops for said gears as the slots 6 and 8 terminate in positions corresponding with 20 the normal positioning of the front edges of said keys, the slots 5 in the followers 3 terminating at the normal positions of the rear edges of said keys. In order to provide for series operation of the 25 gears when the coupler is subjected to buffing forces, the slots 5 in the followers 3 are elongated forwardly of the normal positions of the front edges of said keys an amount corresponding with the distance each gear is adapted to be compressed so that said followers are allowed to move 30 rearwardly upon actuation by the associated drawbar for effecting compression of the gears. Because of the fact that the housing of the front or outer gear has to move rearwardly to effect a compression of the rear gear, the slot 6 in the 35 front cheek plates 7 are desirably elongated, as shown, rearwardly of the rear edge of the associated key 4 to provide for the extra movement of the front follower 3, as compared with the rear follower 3. It will, therefore, be seen that while 40 both the gears are compressed against the keys 4, which act as individual stops when the coupler is subjected to draft forces, the backstop 25 acts as a common stop for both gears under the action of buffing forces, so that said gears are 45 compressed in series directly by the drawbar 21 acting through the front follower 3, the front friction elements 14, the front gear housing 10, yoke bridge wall 27, rear or second follower 3, rear or second friction elements 14, and rear or second housing 50 10 which directly abuts against the backstop 25.

Referring now to the embodiment of my invention illustrated in Figures 3, 4 and 5, a construction involving a pair of gears or cushioning devices 1^a embraced by a tandem yoke 20^a, connected to an associated drawbar 21^a by a horizontal key 22^a, as in the previous embodiment, is disclosed. The only material difference in the present embodiment with respect to the first embodiment is that the slotted followers 3^a for the gears 1^a snugly 55 receive the associated keys 4^a, the movement for said keys and followers being provided by correspondingly elongating the slots 6^a and 8^a in the cheek plates 7^a and 9^a, respectively. The advantage of the present embodiment over the first 60 embodiment is that the assembled mechanism may be shortened by an amount equivalent to the sum of the compressive movements of the two gears 1^a, as the associated followers 3^a are shortened by such an amount, otherwise, the 65 operation of the mechanism is the same as that shown in Figures 1 and 2.

Referring now to the embodiment of my invention illustrated in Figures 6 and 7, a construction is there disclosed involving a pair of cushioning devices or draft gears 1^b, the rearmost of which

has associated therewith a rear follower 28, said cushioning devices and rear follower being embraced by a horizontal yoke 20^b formed with a preferably integral bridge wall 27^b extending between the two gears 1^b and functioning as the rear follower for the front gear and as a follower between the front and rear gears 1^b and may be considered as the rearward portion of an individual yoke for the front gear 1^b.

Each gear 1^b, in the present embodiment, comprises a housing 10^b provided with a slot 5^b receiving a supporting draft key 4^b, which keys function as individual front stops for the gears 1^b, as in the first embodiment, the ends being received in rearwardly elongated yoke slots 3^b 15 permitting relative forward movement of the yoke 20^b on draft and slots 6^b and 8^b in cheek plates 7^b and 9^b, and the sills 2^b of the railway vehicle. The housings 10^b, in the embodiment disclosed, are provided with inclined friction surfaces 12^b engaged by corresponding surfaces 13^b on associated wedge blocks 14^b, said wedge blocks being desirably interlocked with the housings, as in the previous embodiment, urged apart by curved plate springs 15^b, and acted on by release springs 18^b engaging intermediate followers 17^b. Because of the slots 5^b, and the horizontal keys passing through the housings 10^b, the release springs 18^b are desirably helical rather than plate springs, as in the previous embodiment, and disposed above and below, 30 the keys 4^b, as shown most clearly in Figure 6.

As in the previous embodiment, rear stop or rearward limiting means such as a backstop 25^b is provided for limiting rearward movement of the follower 28, while permitting rearward movement of the horizontal yoke 20^b, said backstop being desirably formed to guide the rear end of the yoke, as shown most clearly in Figure 6. In order to support the rear follower 28, a carrier iron 29 is desirably provided beneath said follower, 40 and the rear end of the housing 10^b, said carrier iron being desirably connected to the sills 2^b in any desired manner, as by means of bolts 30 and nuts 31.

The clearance between the keys 4^b and the slots 45 in the yoke, cheek plates and sills, and between the drawbar 21^b and the key 22^b connecting said drawbar and yoke 20^b are desirably as shown in Figure 7. The gears 1^b act in tandem or parallel when the coupler or drawbar is subjected to draft 50 forces, and in series when the coupler is subjected to buffing forces, so that although equal cushioning capacity for absorbing energy is provided for draft and buffing forces, yet a greater, and preferably double the travel is provided for the coupler 55 on buff than on draft. The resistance to movements of the coupler on draft for a full compression of the gears is double, if each gear has the same static closing resistance, that for such a movement of the coupler on buff. If gears having equal travel, but with different static closing resistances, are employed, the resistance on draft to a full closure equals the sum of the static closing resistances of the two gears. The ultimate closing resistance on buff, in such a case, equals 60 the closing resistance of the gear having the greater closing resistance, as will be understood.

Referring now to Figures 8, 9, 10 and 11, I have there shown diagrams representing the cushioning action of the shock-absorbing devices or draft 65 gears 1, 1^a and 1^b. Figure 8 represents the cushioning effect of one of the gears, either 1, 1^a or 1^b, acting by itself, the energy absorbed in closing the gear through a distance *d* to a final closing resistance *f* being represented by a triangle with a 70

base d and an altitude f , the energy absorbed being $\frac{1}{2} df$. Figure 9 shows a similar diagram for the other gear, said diagram being representative of either the gear 1, 1^a or 1^b and showing the amount of energy absorbed by closing the gear through a distance d with a final closing effort f , the energy absorbed being $\frac{1}{2} df$.

Figure 10 represents the action of two gears in series, the gears employed being either 1, 1^a or 1^b, and acting as in any of the embodiments disclosed, the work absorbed, when so acting, under the action of buffing forces applied to the associated drawbar 21, 21^a or 21^b, being represented by a triangle with a base $2d$ and an altitude f , the energy absorbed being df , or the energy absorbed by one gear plus the energy absorbed by the other gear used therewith. In a preferred embodiment, as disclosed, the gears have been shown as of equal energy-absorbing capacity so the energy absorbed with two gears in series and subjected to buffing forces is equal to twice the energy absorbed by one gear, the coupler or drawbar acting through a distance equal to twice the closing movement of one gear and the ultimate closing force being equivalent to the closing force for one gear.

Figure 11 is a diagram representing the energy absorption of the gears when the coupler is subjected to draft forces, said gears being in tandem and the coupler moving through a distance d with an ultimate closing force of $2f$, the total energy absorbed being df , or the sum of the energy absorbed by each individual gear 1, 1^a or 1^b, as the case may be. With gears, as in the preferred embodiment disclosed, having equal, or substantially equal, energy absorbing capacities, the energy absorbed on draft is equal to twice, or substantially twice, the energy absorbed by a single gear, as is the case when the gears are subjected to buffing forces while in series, as represented by the diagram of Figure 10.

From the foregoing disclosure, it will be seen that I have devised railway draft rigging and associated cushioning mechanism of such a character that on buff the drawbar acts on the front mechanism which energizes the succeeding mechanism so that the associated cushioning or shock-absorbing devices then act in series. On draft each cushioning device is energized independently or in tandem. Thus, although equal, or substantially equal capacity, from a standpoint of energy absorption, is provided under both buff and draft, a greater amount of travel is permitted the drawbar for a full closure of the gears on buff than for draft movement. Because of the fact that the resistance builds up for gears in tandem while it is not increased with gears acting in series, the static resistance to draft for a full closure of the gears is equal to the sum of the resistance of the individual gears which are preferably, although not necessarily, similar in construction and capacity.

Although I have disclosed preferred embodiments of my invention, it will be understood that modifications may be made within the spirit and scope of the appended claims.

I claim:

1. In railway draft rigging, in combination with draft sills, a drawbar, a pair of cushioning devices disposed between said sills, a yoke with arms embracing said cushioning devices, a bridge wall connecting the arms of said yoke between said cushioning devices and serving to transmit forces from the front cushioning device to the rear cushioning device on buff and to the front

cushioning device on draft, means connecting said drawbar and yoke for the transmission of draft forces, a key associated with each cushioning device and functioning as front stop means therefor while permitting rearward compressive movement thereof, and means serving as a backstop for the rearmost cushioning device while permitting rearward movement of said yoke, whereby each device is compressed against its key so that said cushioning devices operate in tandem on draft and both are compressed in series against the backstop when the drawbar is subjected to buffing forces.

2. In railway draft rigging, in combination with draft sills, a drawbar, front and rear cushioning devices disposed between said sills, a slotted front follower associated with each cushioning device, a vertical yoke with arms embracing said cushioning devices and front followers, a bridge wall connecting the arms of said yoke, disposed between, and normally in engagement with, the front cushioning device and the front follower of the rear cushioning device, and serving to transmit forces from the front cushioning device to the rear cushioning device on buff and to the front cushioning device on draft, a key connecting said drawbar and yoke for the transmission of draft forces and permitting the drawbar to move rearwardly with respect to the yoke on buff, a key associated with each follower and functioning as front stop means therefor, the slots in said followers being normally elongated forwardly of the front edges of the keys to permit rearward movement of said followers to compress the cushioning devices under the action of buffing forces, and means serving as a backstop for the rearmost cushioning device while permitting rearward movement of said yoke, whereby each device is compressed against its front follower and key so that said cushioning devices operate in tandem on draft and both are compressed in series against the backstop when the drawbar is subjected to buffing forces.

3. In railway draft rigging, in combination with draft sills, a drawbar, front and rear cushioning devices disposed between said sills, a slotted front follower for each cushioning device, a vertical yoke with arms embracing said cushioning devices and front followers, a bridge wall connecting the arms of said yoke, disposed between the front cushioning device and the front follower of the rear cushioning device and serving to transmit forces from the front cushioning device to the rear cushioning device on buff and to the front cushioning device on draft, means connecting said drawbar and yoke, a key closely fitting the slot in each front follower and with its ends received in slots in the draft sills, said draft sill slots terminating at the normal positions of the front edges of said keys, whereby said keys function as front stop means for the cushioning devices, and being elongated rearwardly of the rear edges of said keys to permit rearward movement thereof for compression of the cushioning devices by the drawbar, and means serving as a backstop for the rearmost cushioning device while permitting rearward movement of said yoke, whereby said cushioning devices operate in tandem on draft, with each device compressed against its front follower and key, and both are compressed in series against the backstop when the drawbar is subjected to buffing forces.

4. In railway draft rigging, in combination with draft sills, a drawbar, front and rear cushioning devices disposed between said sills, a yoke with arms embracing said cushioning devices, a bridge wall connecting the arms of said yoke between said cushioning devices and serving to transmit forces from the front cushioning device to the rear cushioning device on buff and to the front

ioning devices disposed between said sills, each cushioning device comprising a slotted housing enclosing resilient and frictional means, a horizontal yoke with arms embracing said cushioning devices, a bridge wall connecting the arms of said yoke between the front and rear cushioning devices and serving to transmit forces from the front cushioning device to the rear cushioning device on buff and to the front cushioning device on draft, means connecting said coupler and yoke for the transmission of draft forces, a key passing through the slot in each housing to function as front stop means for said cushioning devices, the ends of said keys being received in slots in said sills, said sill slots being rearwardly elongated to permit rearward compressive movement of the cushioning devices when the drawbar is subjected to buffing forces, and means serving as a backstop for the rearmost cushioning device, while permitting rearward movement of said yoke, whereby said cushioning devices operate in tandem on draft, with each device compressed against its key, and both are compressed in series against the backstop when the drawbar is subjected to buffing forces.

5. In railway draft rigging, in combination with a drawbar, a pair of cushioning devices, a yoke with arms embracing said cushioning devices, a bridge wall connecting the arms of said yoke between said cushioning devices and serving to transmit forces from the front cushioning device to the rear cushioning device on buff and to the front cushioning device on draft, means connecting said drawbar and yoke for the transmission of draft forces while permitting relative longitudinal movement of the drawbar on buff, means serving as individual front stops for said cushioning devices, and rear stop means for the rearmost cushioning device permitting rearward movement of said yoke, whereby said cushioning devices operate in tandem with each compressed against its front stops and require a relatively great force for full compression on draft and are both actuated in series and compressed against the rear stop means, requiring a smaller force for full compression, when the drawbar is subjected to buffing forces.

6. In railway draft rigging, in combination with a drawbar, a pair of cushioning devices of equal individual travel for full compression, a yoke with arms embracing said cushioning devices, a bridge wall connecting the arms of said yoke between said cushioning devices, serving to transmit forces from the forward device to the rearward on buffing action and serving to transmit forces to the forward device when the drawbar is subjected to draft, means connecting said coupler and yoke for the transmission of draft forces and allowing the drawbar to move rearwardly with respect to the yoke under the action of buffing forces, means serving as individual front stops for said cushioning devices, and means serving as a rear stop for the rearmost cushioning device, whereby equal cushioning capacity is obtained under both buff and draft but a different amount of travel is permitted in one direction than the other.

7. In railway draft rigging, in combination with a drawbar, a plurality of spaced follower-acting means arranged one in advance of another, a plurality of cushioning devices disposed one in advance of the other between said means, stop means for preventing forward movement of the forward follower-acting means from normal position, stop means for preventing rearward

movement of the rear follower-acting means from normal position, said forward follower-acting means being movable rearwardly coextensively with the drawbar on buffing, means disposed between said follower acting means serving as a front stop for the rear cushioning device, means for transmitting buffing force from the forward cushioning device to the rear cushioning device, and means operatively connected to said drawbar and relatively movable longitudinally with respect thereto for causing said rear follower acting means to move coextensively with the drawbar on draft.

8. In a railway draft rigging, in combination with slotted draft sills, a drawbar, yoke-acting means, said drawbar being movable with respect to said yoke-acting means in buffing, means for operatively connecting said drawbar and yoke-acting means for permitting the latter to be actuated by the drawbar on draft, a plurality of cushioning devices arranged one in advance of the other within said yoke-acting means, and a plurality of longitudinally spaced keys extending through said slotted sills, said keys, respectively, forming forward stops for the said cushioning devices, being mounted in slots some of which are appropriately elongated so that said keys will approach each other longitudinally of the draft rigging when the drawbar is subjected to buffing force, and means movable with said yoke-acting means on draft for actuating the foremost one of said cushioning devices and serving to transmit forces from the front cushioning device to the rear cushioning device on buff, said yoke-acting means serving to actuate the rearmost of said cushioning devices on draft.

9. In railway draft rigging, in combination with a drawbar, a plurality of cushioning devices arranged one in advance of the other and each including friction elements, means constituting individual front stops for said cushioning devices functioning during the entire draft movement, means constituting a rear stop for the rearmost cushioning device, and means operatively connected to said drawbar and relatively movable longitudinally with respect thereto for simultaneously actuating said cushioning devices in tandem upon draft movement of the drawbar, and including means for transmitting buffing force from the forward cushioning device to the rear cushioning device.

10. In railway draft rigging, in combination with a drawbar, a plurality of cushioning devices disposed one in advance of the other, forward stop means for each of said cushioning devices, rear stop means for the rearmost of said cushioning devices, yoke-acting means for actuating said cushioning devices in tandem on draft and including means to transmit forces from the front cushioning device to the rear cushioning device, and means operatively connecting said drawbar and yoke-acting means on draft and permitting relative longitudinal movement therebetween on buff, whereby buffing movement of said drawbar actuates the devices in series and is thereby greater than the draft movement thereof.

11. In railway draft rigging, in combination with a pair of longitudinally spaced cushioning devices, a drawbar directly acting on the foremost device on buff, means for actuating said cushioning devices in tandem on draft, including means for transmitting buffing force from one device to the other in series, means serving as individual front stop means for said cushioning devices, and means serving as common rear stop

- means for said cushioning devices, whereby a greater amount of force is available for cushioning draft forces than for cushioning buffing forces.
- 5 12. In railway draft rigging, in combination with a drawbar, a plurality of cushioning devices spaced by a key-supported follower and adapted to be simultaneously energized upon draft and buffing movements of the drawbar, said follower acting upon movement of the drawbar in one direction for transmitting forces from one of said cushioning devices to another cushioning device in series, and means acting upon movement of the drawbar in the opposite direction to energize each of said cushioning devices independently in tandem.
- 10 13. In railway draft rigging, in combination with a drawbar, a plurality of cushioning devices spaced by a key-supported follower serving to transmit forces from one cushioning device to another for causing said devices to act in series upon movement of the drawbar in one direction, and means including a yoke with a portion disposed between said cushioning devices for causing the latter to act in tandem on movement of the drawbar in the opposite direction.
- 15 14. In railway draft rigging, in combination with a drawbar, a pair of devices of substantially equal capacity for cushioning draft and buffing movements, and means for energizing said devices to effect substantially equal cushioning capacity thereof for said drawbar in draft and buffing, said last-named means including means operating upon travel of the drawbar of a given extent in one direction to fully energize said devices, and means operating upon a different extent of travel of the drawbar in the opposite direction to fully energize said devices.
- 20 15. In railway draft rigging, in combination with a drawbar, a pair of devices of substantially equal capacity for cushioning draft and buffing movements of the drawbar, and means for energizing said devices on draft and buffing movements of the drawbar, said last-named means being adapted to effect equal cushioning capacity of said devices both in draft and in buffing, while affording greater resistance to movement of the drawbar in one direction than in the other.
- 25 16. In railway draft rigging, a coupler, a pair of cushioning devices of substantially equal capacity, and means including mechanism for operatively connecting the coupler to the cushioning devices and the cushioning devices to an associated vehicle to develop the full capacity of the cushioning devices under pull and under buff and to cause the same to operate over a relatively long travel in buff and short travel in pull.

BYERS W. KADEL.
